UNITED STATES PATENT OFFICE.

ROBERT SCHLAEPFER, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

COOLING OF PISTONS.

1,267,702.

Specification of Letters Patent. Patented May 28, 1918.

Application filed September 21, 1914. Serial No. 862,830.

To all whom it may concern:

Be it known that I, ROBERT SCHLAEPFER, engineer, a citizen of the Republic of Switzerland, residing at Winterthur, Canton of Zurich, Switzerland, have invented the following-described Improvements in or Relating to the Cooling of Pistons.

The improvements relate to piston-cooling apparatus of the kind wherein a tube or 10 tubes secured to the hollow piston are connected telescopically with a source of water supply and exit and more especially to that particular type of piston-cooling apparatus wherein moderate water pressures are used, 15 and air mixed with the water or liquid passes through the telescopic tubes and pistons.

The object of the invention is to return the water accumulating on the telescopic tubes to the water supply and thereby provide 20 against the admixture of the same with the oil in the crank-case of the engine.

In the accompanying drawing an exemplary embodiment of the invention is illustrated in diagrammatic manner.

25 The piston indicated by 1 may be assumed to be the piston of an internal combustion engine or like reciprocating member requiring to be maintained at a predetermined temperature. The water supply and exit apparatus comprises two chambers marked 2 and 3, respectively, connected together by the common outflow pipe 4. The telescopic tubes 5 and 6, connected to the interior cooling space 1^a of the piston, are arranged to 30 reciprocate telescopically within the upper portions of the chambers 2 and 3, and may be made to fit more or less snugly therein by means of the packing rings marked 7. Water is introduced into the tube 5 by means of a 35 small pipe 8, which directs a jet of water lengthwise through the tube and into the chamber 1^a, and such jet carries air with it

so that the cooling medium in the interior of the piston consists of a mixture of air and water which may escape through the outlet 45 tube 6 into the outlet chamber 3. The water also runs back through the tube 5. The air is drawn into the supply receptacle 3 through an air inlet 9 in the receptacle 2, and escapes through the outlet 10 in the other receptacle. 50 Water particles adhering to the tubes 5 and 6 are caught in the chambers 11 disposed above the rings 7, and around the lower portions of the tubes, where they enter the chambers and such water accumulating in these 55 chambers flows back to the receptacles 2 and 3, respectively, through the drain pipes 12.

It will be understood, as above stated, that the illustrative apparatus above described is merely schematic and that the principle 60 thereof can be incorporated in various forms of structures.

Claims:

1. In apparatus of the kind described, a 65 water-supply apparatus, a reciprocating piston having a sliding joint with such apparatus, a chamber above the joint and surrounding the reciprocating part thereof and a drainage passage from such chamber to the water-supply apparatus.

2. In apparatus of the kind described, the 70 combination of a piston having a cooling chamber, a reciprocating tube connected to the piston, a stationary casing wherein said tube reciprocates, a joint between the outside 75 of the tube and the casing, a catch-basin above the tube, and a drainage passage from such chamber.

In testimony whereof, I have signed this 80 specification in the presence of two witnesses.

ROBERT SCHLAEPFER.
